UNITED STATES PATENT OFFICE.

THOMAS SINGLETON, JR., OF NEW BEDFORD, MASSACHUSETTS, ASSIGNOR
TO THE MOUNT WASHINGTON GLASS COMPANY, OF SAME PLACE.

DESIGN FOR AN ORNAMENTAL GLASS DISH.

SPECIFICATION forming part of Design No. 22,287, dated March 14, 1893.

Application filed September 22, 1892. Serial No. 446,841. Term of patent 7 years.

To all whom it may concern:

Be it known that I, THOMAS SINGLETON, Jr., of New Bedford, in the county of Bristol and State of Massachusetts, have invented and produced a new and original Design for Ornamented Glassware, of which the following is a specification, reference being had to the accompanying drawings, illustrating the same, and showing my design embodied in a bowl or shallow dish.

Figure 1 is a plan of a dish containing my design, and Fig. 2 is a sectional view of the same.

The leading feature of my design consists in a star the middle of which is ornamented by a rose like figure, the points of the star extending substantially to the rim of the dish, and a series of rose like figures between the points of the star.

A is the ornamented star, and covers nearly

the entire bottom of the dish; its points $a a'$ &c. each extend well upward to the rim of the dish, as shown, and between the points of the stars are a series of rose like figures B B', &c., which run into the margin of the dish. The dish is separated into fields of various shapes by crosswise indentations $c c' c^2 c^3$, and is ornamented with a series of diamond shaped figures 1, 2, 3, 4, &c., and the center of the star is filled in with a conventionalized rose. The edge of the dish is indented, and converging indentations f center at the extreme points of the star.

What I claim is—

The design for an ornamented glass dish as herein shown and described.

THOMAS SINGLETON, JR.
